FIG. 5

UNITED STATES PATENT OFFICE

JOHN P. TARBOX, OF PHILADELPHIA, PENNSYLVANIA, ASSIGNOR TO EDWARD G. BUDD
MFG. COMPANY, OF PHILADELPHIA, PENNSYLVANIA, A CORPORATION OF PENN-
SYLVANIA

VEHICLE BODY

Application filed September 1, 1927. Serial No. 216,909.

This invention relates to an automobile body construction of the "composite" type.

The present practice in composite body building is to first form the skeleton wooden frame of the body, so shaping and sizing the frame members that the contour of the body and the dimensions of the door and window openings will be defined thereby, and then covering said skeleton frame with sheet metal panel strips. This practice has required a large amount of steaming of the frame members to obtain curvature as well as much fine fitting and cutting thereof in defining the door and other openings. It has been proposed to eliminate the necessity of accurately constructing the frame by applying thereto a one piece sheet metal stamping having continuous openings formed therein, the edges of which are flanged to define the jamb and the limits of the opening independently of the frame. However, since stamping must be drawn to a depth substantially equal to the full depth of the body wall there still remains the necessity of imparting curvature to the frame members and also of having such members of relatively thick rectangular section.

The principal object of the present invention is to provide a composite body construction wherein the frame and its formation may be greatly simplified and the rectangular section of the frame members materially reduced.

Another important object is to provide a composite body construction wherein the contour of the body and the limits of the door and window openings will be defined by the sheet metal paneling substantially independently of the wooden frame.

Other objects and advantages will become apparent hereinafter.

It is proposed in carrying out the invention to construct the frame of relatively thin rectangular section, the posts being substantially straight while the headers and sills are curved slightly to furnish in part the longitudinal curvature of the body. The frame members may be joined together by butt or lap joints and reinforced by suitable brackets. The entire outer panel on each side of the body is formed of a one piece stamp-

ing having openings therein for the closures. The edges of these openings are inwardly flanged during the stamping operation, thereby forming continuous jambs for the laterally movable closures. However, the depth of the jambs thus formed are not the full depth of the side of the body, being less than such depth by the thickness of the relatively thin frame, to which it may be secured by rabbed flanges.

An embodiment of the invention is illustrated in the accompanying drawings wherein—

Figure 1 is a side elevational view of a body constructed in accordance with the invention;

Figs. 2, 3, 4, 5 and 6 are sectional views taken respectively on the corresponding section lines of Fig. 1, looking in the direction of the arrows;

Fig. 7 is a detail of the inside of the body at the wheel housing, showing the connection between the rear post and the sill; and

Fig. 8 is a sectional view taken approximately on the line 8—8 of Fig. 1 through the body paneling and framing.

The framework comprises the sills 10, front or A posts 11, intermediate or B—C posts 12, and rear door or D posts 13. The longitudinally extending members 14 form the roof headers. All of these elements are secured together by either lap or butt joints in any well known manner, and may, wherever desired, be reinforced by brackets. The D posts are connected to the sills by means of angle brackets 15, which extend downwardly and forwardly from the lower end of the posts to allow for the wheel housing "kick-up". The sills 10 are bolted or otherwise suitably secured to the chassis members 16, which being of angle formation form a support likewise for the floor boards 17.

This frame may embrace substantially straight posts since the vertical curvature of the body is furnished by the paneling. It is obvious that this fact alone materially simplifies the body construction. Although the sill members need curving to a slight extent, the major portion of the longitudinal curva-

ture of the body may also be formed by the paneling. It should be noted that the frame members are of relatively thin rectangular section thereby greatly reducing the weight 5 of the body, as well as the cost of the material forming the same.

Combined with this frame is the paneling, which is made up of one piece stampings on each side of the body extending from the 10 cowl to the rear part of the tonneau. The stampings, in the instance herein illustrated, are provided with front and rear door openings 18 and 19, respectively, and quarter window openings 20. Of course, it is understood 15 that the openings and their number will vary with the style of body, and that although a sedan body is shown, the invention is applicable to other styles as well. The panel during the stamping operation is formed at 20 those portions flanking the sills, posts and headers with a general channel cross section.

The portion of the panel adjacent the A post, while in the general form of a channel, has the forward part of its base and its forward 25 wall formed on a curve to impart symmetry and grace to the body. The rear part 23 of the base is inwardly offset to form a rabbet for the door overlap, while the rear wall 24 is provided with a rabbeted flange 25. 30 The panel is secure to the A post by screws or other means extending through the forward wall 22 and the rabbeted flange 25. The forward wall is connected to the front face of the post, while the rabbeted flange is connected to 35 the outer face of the post, having its rear edge turned inwardly to effect a neat joint with the post. Upon the inner face of the post the windshield frame is secured, the forward edge of which extends around the post in 40 overlapping relation with the forward wall 22 of the panel.

At the B-C post the panel is of simple channel section, the base 27 of which lies approximately on a line with the offset base 45 part of the A post panel, so that the doors will lie within the general exterior plane of the body. The forward and rearward walls 28 and 29 are each provided with rabbeted flanges 30 and 31 which are secured to the 50 outer face of the post 12.

The paneling does not have a channel formation at the D post except at the location of the quarter window. It is formed at the other points with an inturned rabbeted flange 55 32 corresponding to the forward wall of the channel portion adjacent the window opening. The lower part of the panel has the flange 32 forwardly extended and secured to the bracket 15, in order to allow for the wheel 60 housing "kick-up". In forming the channel portion of the panel adjacent the window opening the base 33 of the channel is provided with an inward offset forming a rabbet for the door overlap while the forward 65 wall 34 has the rabbeted flange 35 corre-

sponding to the similar flanges at the other post portions of the panel. The rear wall 36 extends straight inwardly and is secured to the rear face of the post 13 while the flange 35 is secured to the outer face thereof. 70 Superimposed and secured upon the wall 36 is the guide 37 for the sliding quarter window. Of course, if it was desired to use a laterally movable quarter window the panel could be formed with rabbeted offsets to provide a continuous jamb therefor.

The channelled portion of the panel adjacent the header has the inwardly offset base 38 forming a part of the continuous door and window frames, as well as the flanged side wall 39. The upper wall 40 of the channel is attached to the top edge of the header and the flanged bottom wall 39 to the outer side thereof. The roof panel 41 rests upon the upper wall 40 and has its inner edge downwardly flanged and its outer edge in the form of a bead, whereby the roof in effect embraces the top of the body.

Along the bottom of the panel, the channel is formed of a downwardly and inwardly inclined base wall 42 and oppositely flanged side walls 43 and 44. The flanges formed on such walls are secured to the outside of the sills and have inwardly bent portions overlying the top and bottom edges of the sill. 90

From the foregoing it will be seen that in all cases the jamb of the door opening is formed by the combined depth of the inwardly flanged portions of the panel and the thickness of the wooden frame members; for example, the jamb is formed in the front post region by the portions 24 and 11, at the intermediate post by the portions 29 or 28 and 12, and at the rear door post by the portions 34 and 13. In each case the width of the jamb is substantially the combined depth of the channel formed by the outer paneling and the thickness of the wooden frame members. The foregoing description is thought to clearly bring out the structural features of the embodiment. This invention will be seen to differ materially from other suggested constructions contemplating the employment of paneling formed from one piece stampings so that continuous door or other frame openings may be provided therein and their limits defined independently of the frame. 110

In the heretofore suggested constructions the stamping is formed by a deep draw so that the flanges of the openings will constitute jamb faces of a depth equal to the full depth of the body side. However, the deep drawing of the panel is attended with difficulty and in addition, the frame members being of relatively large rectangular cross section the weight of the body is increased. In the present construction the panel, while defining the door and other openings so that accurate fits will be obtained for the laterally movable closure members, does not require 120 125 130

- such depth of draws in forming the flanges of the openings. The coacting between the frame and the sheathing or paneling is such that in effect the frame forms a light, thin 5 inner panel for the outer panel, and reduces the depth of the draw of the latter by substantially the thickness of the frame members. This is accomplished without losing the advantages of having the paneling define 10 the closure openings, since the main or contacting surfaces of the jamb are formed by the panel, and such portions as are of wood are easily accessible. Therefore, the frame does not need to be constructed with that 15 degree of accuracy in cutting and joining usually required in composite body constructions. Furthermore, since the major portion of the body curvature is furnished by the paneling the steaming of the wooden frame 20 members is reduced to a minimum. Since the cross section of the frame members is reduced, the cost thereof, as well as their weight, is naturally lessened besides permitting such members to be of a lower grade 25 stock. The construction also effects a still further economy, as well as a convenience, since the frame members eliminate the necessity for upholstery tacking strips.
- The advantages of the one piece panel accurately defining the closure openings and capable of being formed in a single stamping operation are so apparent as not to require specific mention. The elimination of 30 the deep draw has already been set forth.
- 35 The panel is by itself of great strength but when connected to the frame, (or by another designation, its inner wooden panel), a box girder structure results at all essential parts of the body.
- 40 This construction is of particular advantage in connection with modern automobile bodies which are of curved contour both vertically and horizontally. The showing in Figure 1 and in the sections shown in the remaining figures clearly indicates the application 45 of the invention to this type of body, in which the outer paneling is curved longitudinally and vertically to give the body its contour.
- 50 The following claims are added with the understanding that all modifications and adaptations within their scope form a part of my original invention.
- 55 What I claim as new and useful is:
1. An automobile body wall construction comprising a substantially flat rectilinear wooden main frame member and a sheet metal facing therefor, the sheet metal facing being outwardly bowed to the contour of the body and formed with inwardly extending flanges of a depth less than the thickness 60 of the body wall connected to said frame member to form therewith a hollow frame structure of substantially the full thickness 65 of the body wall.
  2. An automobile body construction comprising a wooden main frame made up of substantially flat rectilinear members, and a one piece sheet metal panel bowed outwardly to give contour to the body and having a closure opening therein having a transverse extending jamb, the edges of said panel in said opening being in the form of a continuous turned flange forming part of the jamb and of such proportions that its depth in combination with the thickness of the frame members adjacent thereto forms a closure jamb of substantially the full thickness of the body wall. 70
  3. An automobile body construction comprising a wooden main frame made up of substantially flat rectilinear members, and a one piece sheet metal panel bowed outwardly to give contour to the body and having those portions which are adapted to lie adjacent the wooden frame members in the form of inwardly presenting channels, and so arranged with respect to said frame members that the thickness of the body wall will be equal to the combined depth of the channel 85 and the thickness of the adjacent frame member, whereby the contoured metal panel forms with the adjacent frame members hollow box sectioned structures. 90
  4. An automobile body construction comprising a wooden frame, and a one piece sheet metal panel bowed outwardly to give contour to the body, said frame including substantially flat rectilinear vertical and longitudinal members, said panel having a closure opening therein within its outer marginal edges, the marginal outer edges of the panel and the peripheral edges of the closure opening of the panel being formed into inwardly presenting channels adapted to be secured to said frame members with the bottoms of the channels spaced from the frame members, the combined depth of the channels and the thickness of the frame members defining the thickness of the jamb of the closure opening. 100
  5. An automobile body construction comprising vertical and longitudinal substantially flat rectilinear wooden members forming a frame, a one piece sheet metal panel outwardly bowed to the contour of the body and having a closure opening therein, the peripheral edges of which are in the form of inwardly facing channels, said panel being secured to said frame members by rabbeted flanges on the walls of said inwardly facing channels, and constituting with said frame members a continuous jamb for a laterally movable closure of a depth equal substantially to the combined depth of the channels 115 and the frame members. 120
  6. An automobile body comprising a wooden main body frame including sills and post members each composed of substantially rectilinear flat wooden stringers, and

outwardly bowed metal facings secured to said stringers and constituting the exterior surface of said body and giving it contour, and by their connection with the stringers forming therewith hollow frame structures, the dimension transversely of the body of the hollow space of said structures varying in accordance with the outer contour of the body.

7. An automobile body comprising a wooden main body frame, the sills and posts of which are each composed of substantially rectilinear flat wooden stringers, and outwardly bowed metal facings for said stringers die stamped to have their body portions disposed outwardly of said stringers, the facings and stringers being secured together substantially throughout their length to form hollow frame structures, the dimension transversely of the body of the hollow space of said structures varying in accordance with the outer contour of the body.

In testimony whereof he hereunto affixes
his signature.
